Attorney

United States Patent Office.

JOSEPH TRUMP, OF SPRINGFIELD, OHIO.

Letters Patent No. 101,947, dated April 12, 1870.

IMPROVEMENT IN COTTON-SEED PLANTERS.

The Schedule referred to in these Letters Patent and making part of the same.

To all whom it may concern:

Be it known that I, JOSEPH TRUMP, of Springfield, Clarke county, State of Ohio, have invented certain new and useful Improvements in Cotton-seed Planters; and I hereby declare the following to be a sufficiently full, clear, and exact description thereof to enable one skilled in the art to which my invention appertains to make and use it, reference being had to the accompanying drawings making part of this specification.

My invention consists of the following devices, to wit:

First, revolving barrel-shaped hoppers for containing the seed, fitted with projecting bars for agitating the seed and preventing clogging.

Second, a stationary diaphragm attached to the frame of the machine and fitted with a revolving toothed "picker" for throwing out the seed.

Third, a revolving case, which also forms the supporting wheel of the machine and runs in the furrow, the case being constructed in two parts, V-shaped on the periphery, and separated sufficiently to form a circular opening for the passage of the seed to the bottom of the furrow.

Fourth, a peculiar construction of covering share.

Fifth, a slide and hand-lever for regulating the delivery of the seed.

In the accompanying drawings—

Figure 1 is an elevation of the machine, with the case on one side removed to exhibit the interior.

Figure 2 is an axial section through the revolving hoppers and case.

Figure 3 is a perspective view of the covering share.

Figures 4 and 5 exhibit modifications in the construction of the revolving picker.

Figure 6 is a detached perspective view of the valve-slide and lever for regulating the delivery of the seed.

A is the beam of the machine, and B the handles.

The diaphragm C is attached to the beam in the manner shown, and carries the share D for forming the furrow.

The diaphragm also connects to the handles by means of stay E, and is provided with a journal-box, F, in which the shaft of the revolving hoppers and case rotate.

The shaft G carries the barrel-shaped seed-hoppers H H', to which are attached the parts I I' of the case, which forms the supporting-wheel of the machine, and serves to give motion to the revolving picker J for delivering the seed, which is journaled in the diaphragm C, and rotated by means of spur-wheels K on the part I of the case, and pinion L on the picker-shaft.

The parts I I', when together, are V-shaped on the edge, and run in the furrow behind the share D, and are separated, as shown, to permit the passage of seed from the hoppers to the furrow as it is thrown out by the picker J.

As this passage is covered by the share D in front and cases I I' at the sides, the seed cannot be disturbed by wind, &c.

The hoppers H H' are first supplied with seed, and, if necessary, fertilizing material also, through the openings h h', which are then closed by sliding covers.

The hoppers are also fitted with bars M for agitating the seed.

An aperture, e, is cut through the diaphragm C for the delivery of the seed, and this is governed by the sliding-valve N, which, by means of lever O and handle P can be regulated so as to limit or entirely stop the delivery of the seed.

The seed is thrown out by the projecting points on the picker J, and, if necessary to plant the seed in bunches, the picker is constructed as shown in either fig. 4 or fig. 5.

The share which follows the machine is constructed with blades Q Q' for closing up the furrow and blades R R' for leveling off the ground.

This may be raised entirely off the ground by means of string S, as it is made to swing on the shaft G.

By reason of the shape of the hoppers H H' and by action of the bars M the seed is constantly agitated and delivered to a position over the revolving picker, and clogging is also prevented.

I claim herein as new and of my invention—

1. The revolving barrel-shaped hoppers H H' h h', fitted with bars or projections M, as and for the purpose described.

2. The stationary diaphragm C and revolving picker J, operated as described and for the purpose set forth.

3. The revolving case I I', constructed and operating substantially in the manner and for the purpose set forth.

4. The covering-share Q Q' and R R' in the described combination with shaft G.

5. The slide N operated as described, in combination with the revolving picker J.

In testimony of which invention I hereunto set my hand.

JOSEPH TRUMP.
